UNITED STATES PATENT OFFICE.

LELAND F. GOODSPEED, OF MILWAUKEE, WISCONSIN, ASSIGNOR TO MILWAUKEE LOCOMOTIVE MANUFACTURING COMPANY, OF MILWAUKEE, WISCONSIN, A CORPORATION OF WISCONSIN.

GASOLENE-TANK.

1,073,676.

Specification of Letters Patent. Patented Sept. 23, 1913.

Application filed February 17, 1912. Serial No. 678,321.

To all whom it may concern:

Be it known that I, LELAND F. GOODSPEED, a citizen of the United States, residing at Milwaukee, in the county of Milwaukee and State of Wisconsin, have invented a certain new and useful Improvement in Gasolene-Tanks, of which the following is a full, clear, concise, and exact description, reference being had to the accompanying drawings, forming a part of this specification.

My invention relates to tanks for containing liquids such as liquid fuels, and is directed toward improved outlet mechanism therefor. I contemplate that the particular use of my structure will be as a gasolene tank for association with an internal combustion engine for I find that it is particularly susceptible of the control required in such an instance.

The features of my invention consist in the disposition of the outlet valve inside the tank so that it will always be thoroughly protected and will be out of the way, and in the provision of sealing means for closing the vent for the admission of air required to displace the liquid.

By the use of my invention I am enabled to not only close the outlet for the fuel, but also to close the inlet for the air and in this way the tank may be absolutely sealed against leak.

It is a feature of my invention that I embody the ideas of my invention in a simple and inexpensive structure and I make the mechanical features involved the subject matter of some of the more specific of the appended claims.

My invention is illustrated in the accompanying drawings in which—

Figure 1 is a plan view of the tank; Fig. 2 is a side elevational view thereof; Fig. 3 is a sectional view thereof taken on the plane of the line 3—3 of Fig. 1, this section being drawn on a larger scale; Fig. 4 is a plan view of the sealing means with some of the parts removed; Fig. 5 is a sectional view taken on the plane of the line 5—5 of Fig. 3; and Fig. 6 is a perspective view of the wrench which may be employed for actuating the parts.

Like reference characters are applied to the same parts throughout the various figures.

Referring first to Figs. 1 and 2, it will be seen that the tank is illustrated at 7 and that

it is provided with an inlet 8, straps 9, 9, and a handle 10 by which it may be carried.

The valve features are best illustrated in Figs. 3, 4 and 5. It will be seen that toward one end of the tank the top and bottom are provided with alining openings 11 and 12, respectively. A fitting 13 is disposed in the upper opening 11 and is secured in place by means of rivets 14, 14. This fitting 13 is in the form of a dished annulus and is provided with an axial downwardly extending tubular boss 15 which, as shown, projects into the tank. A fitting 16 is disposed in the lower opening 12 and is secured in place by means of rivets 17, 17. This fitting is provided with a central passageway 18 which is adapted to be associated with a coupling 19 held in place by a union 20, this coupling being connected with the device to be supplied from the tank by means of the pipe 21.

The upper part of the fitting 16 has an enlarged bore 22 and the part between the bore 22 and the passageway 18 forms a conical valve seat 23. A valve stem 24 is screw-threaded and engages with threads in the bore 22, the upper part of this stem being smooth and journaled in the boss 15 of the fitting 13. The lower end of the stem 24 is reduced as illustrated and is provided with a head 26 which forms a valve coöperating with the valve seat 23. The lateral passageways 27, 27, connect the valve chamber, in which the valve 26 acts, with the interior of the tank so that the liquid held thereby may flow freely past the valve when the valve is open. The boss 15 and the top of the fitting 16 are connected by a tightly fitting tube 28, which serves to align these parts, this tube being provided with openings 29, 29 to admit of free circulation.

At the top, the stem 24 is provided with a transverse slot 30 into which a key 31, extending downwardly from the underside of a hood 32, is disposed. This hood fits loosely within the rim of the annular fitting 13, as illustrated, and it is provided with a depression 33 in the top thereof, this depression being square for the reception of a wrench such as the end 34 of the device shown in Fig. 6. It will be seen that when the hood 32 is turned the valve stem 24 will be turned and, due to its threaded engagement with the fitting 16, will be raised or lowered depending upon the direction of the turning. The key and slot connection be-

tween the hood and the stem admits of the vertical movement of the stem without displacement of the hood within proper range.

A compressible gasket 35 is disposed in the base of the dished annulus 13 so that the hood 32 may rest upon it and a helical spring 36 is disposed co-axially within the hood between the underside thereof and the gasket. A cap 37 screws on the outside of the rim of the fitting 13 and fits down over the hood 32 so as to clamp it in place as shown. The cap 37 is provided with peripheral lugs 38, 38 so as to facilitate screwing the cap down. The cap is provided with a square central opening 39, which is larger than the depression 33 and is adapted for the reception of a wrench such as the end 40 of the device shown in Fig. 6. By the use of a wrench this cap may be clamped down tightly and may hold the hood down positively against and somewhat embedded in the compressible gasket. It will be seen that when the cap is loosened the spring will raise the hood away from the gasket. The cap is provided with openings 41, 41 for the admission of air and the base of the fitting 13 is provided with holes 42, 42 for the passage of air, as will be pointed out presently.

It will now be seen that the outlet 18 is controlled by turning the hood one way or the other, for instance, when the hood is turned as far as it will go in a clockwise direction, the valve 26 is positively closed. However, at this time the spring holds the hood up away from the gasket and air may enter the tank through the passageways 41, 41 and the passageways 42, 42. The hood occupies this position also when the valve 26 is opened. When the valve is closed, as just pointed out, however, it is also desirable to seal the tank against the entry of air and this is done by screwing down the cap 37 and by tightening it by means of the wrench. This brings down the hood tightly against the gasket, against the tension of the spring, and the connection to the outer atmosphere is positively cut off. When it is desired to get liquid from the tank the wrenches are inserted to first loosen the cap and then to turn the hood. The result will be the opening of the valve and the opening of the inlets to permit the flow of the contents of the tank.

A cap 43 may be suspended from the tank by means of the check flexible chain 44 and this cap may be substituted for the union 20 when the tank is removed from the system which it supplies.

I claim as new and desire to secure by Letters Patent:

1. In a fuel tank, a casing having an opening in the top thereof, a cupped bushing set in said opening, an alining outlet in the bottom of said casing, a valve controlling said outlet, a stem for said valve

mounted in said bushing, a washer in said bushing, a hood fitting down upon said washer and being mechanically connected with said stem, and means for clamping said hood down upon said washer, there being openings in the base of said bushing. 70

2. In a fuel tank, a casing having an opening in the top thereof, a cupped bushing set in said opening, an alining outlet in the bottom of said casing, a valve controlling said outlet, a stem for said valve mounted in said bushing, a washer in said bushing, a hood fitting down upon said washer and being mechanically connected with said stem, and a cap threading on the outside of said bushing and engaging the top of said hood to clamp it down upon the washer, there being communication between the inside of the hood and the inside of the casing. 80

3. In a fuel tank, a casing having an opening in the top thereof, a cupped bushing set in said opening, an alining outlet in the bottom of said casing, a valve controlling said outlet, a stem for said valve mounted in said bushing, a washer in said bushing, a hood fitting down upon said washer and being mechanically connected with said stem, a spring disposed between the underside of said hood and the base 95 of said bushing, and means for clamping said hood down upon said washer, there being openings in the base of said bushing. 90

4. In a fuel tank, a casing having an opening in the top thereof, a cupped bushing set in said opening, an alining outlet in the bottom of said casing, a valve controlling said outlet, a stem for said valve mounted in said bushing, a washer in said bushing, a hood fitting down upon said washer and being mechanically connected with said stem, means for clamping said hood down upon said washer, there being openings in the base of said bushing, and a squared recess in the top of said hood 110 and a larger coaxial squared opening in said clamping means. 100

5. In a fuel tank, a cupped fitting at the top thereof, a fitting in alinement therewith at the bottom, said last named fitting having an outlet opening, a valve stem mounted in said fittings and threaded in one of them, a hood in the upper fitting mechanically connected with said stem, a cap for clamping said hood down upon 120 said upper fitting, and a valve on said stem for controlling said opening. 115

6. In a fuel tank, a cupped fitting at the top thereof, a fitting in alinement therewith at the bottom, said last named fitting having an outlet opening, a valve stem mounted in said fittings and threaded in one of them, a hood in the upper fitting mechanically connected with said stem, a cap for clamping said hood down upon 130 said upper fitting, and a valve on said stem for controlling said opening. 125

- upper fitting, and a valve on said stem for controlling said opening, there being ports connecting the inside of said tank with the inside of the hood.
- 5 7. In a fuel tank, a cupped fitting at the top thereof, a fitting in alinement therewith at the bottom, said last named fitting having an outlet opening, a valve stem mounted in said fittings and threaded in one of them, a hood in the upper fitting mechanically connected with said stem, a washer between the hood and the base of the fitting, a spring between the under side of the hood and the base of the fitting, a cap for clamping said hood down upon said upper fitting, and a valve on said stem for controlling said opening, there being ports connecting the inside of said tank with the inside of the hood.
- 10 8. In a fuel tank, a cupped fitting at the top thereof, a fitting in alinement therewith at the bottom, said last named fitting
- 15 on said stem for controlling said opening, there being ports connecting the inside of said tank with the inside of the hood.
- 20 9. In a fuel tank, a cupped fitting at the top thereof, a fitting in alinement therewith at the bottom, said last named fitting

having an outlet opening, a valve stem mounted in said fittings and threaded in one of them, a hood in the upper fitting mechanically connected with said stem, a washer between the hood and the base of the fitting, a spring between the under side of the hood and the base of the fitting, a cap for clamping said hood down upon said upper fitting, and a valve on said stem for controlling said opening, there being ports connecting the inside of said tank with the inside of the hood.

In witness whereof, I hereunto subscribe my name this 15th day of February, A. D. 1912.

LELAND F. GOODSPEED.
